UNITED STATES PATENT OFFICE.

BLAIR HARDESTY, OF SAVANNAH, GEORGIA.

SHOE-HEEL WEAR-RESISTING AND ANTISLIPPING DEVICE.

1,322,015.

Specification of Letters Patent.

Patented Nov. 18, 1919.

Application filed January 20, 1919. Serial No. 272,041.

To all whom it may concern:

Be it known that I, BLAIR HARDESTY, a citizen of the United States, residing at Savannah, in the county of Chatham and 5 State of Georgia, have invented certain new and useful Improvements in Shoe-Heel Wear-Resisting and Antislipping Devices; and I do declare the following to be a full, clear, and exact description of the invention, 10 such as will enable others skilled in the art to which it appertains to make and use the same.

My invention has for its object to provide an extremely simple and inexpensive, yet 15 highly efficient and durable device for embedding in rubber and fiber heels to resist wear and to prevent slipping; and with this object in view, the invention resides in the novel features of construction and unique association of parts herein fully described and claimed.

Figure 1 of the accompanying drawing is a bottom plan view of a heel and the invention embedded therein.

25 Fig. 2 is a vertical section on the plane of the line 2—2 of Fig. 1.

Figs. 3 and 4 are detail transverse sections on the planes designated by the lines 3—3 and 4—4, respectively, of Fig. 2.

30 Fig. 5 is a perspective view of the wear resisting and anti-slipping device.

Fig. 6 is an elevation of the plate from which the device is formed.

In the manufacture of the invention, an 35 elongated metal plate 1 has one of its ends 2 bent laterally and provided with a notch 3, whereby a pair of calks 4 are formed, for disposition at the tread surface of the heel as shown. The other end 5 of the plate 1 40 is bent laterally in the same direction as the end 2 and at 6 is further bent outwardly at right angles to provide a wear resisting plate whose surface is by preference roughened at 7.

45 The device is embedded in a rubber or fiber heel 8 with the calks 4, and the wear plate 6 exposed at the tread of said heel, said plate being located at the point liable to receive most wear.

50 In order to permit effective anchorage of the device, an opening 9 is preferably

formed in the body portion of the plate 1 and in its bent end 5, so that the rubber or material on opposite sides of said body portion may be united by the material within 55 said opening, and it will be observed that the same result is obtained by the provision of the notch 3.

By constructing the device in the manner shown or in any adequate manner which includes a body or anchor member, calk means at one end of said anchor member, and a wear plate joined to the other end thereof, a highly effective device is provided, since when the weight of the user is placed upon 65 the heel and the latter compresses, the plate 6 has a tendency to force upwardly on the rear end of the device thus slightly canting the latter and tending to project the calk means 4 for anti-slipping purposes. It also 70 will be observed that the mere compression of the heel will expose the calks for proper operation; and the roughened lower surface of the plate 6 will also assist materially in preventing slippage. 75

Since probably the best results are obtained from the details shown and described, they may well be followed, but within the scope of the invention as claimed, numerous minor changes may well be made. 80

What is claimed is:

1. In a wear resisting and anti-slipping device for cushion heels, an elongated plate having one end bent laterally and formed to provide relatively sharp calks, the other end 85 of said plate being bent laterally in the same direction and further bent outwardly at right angles to the laterally bent portions to form a wear plate.

2. In a wear resisting and anti-slipping device for cushion heels, an elongated plate having one end bent laterally and notched to provide calk means, the other end of said plate being bent in the same direction and further bent outwardly at right angles to 95 form a wear plate.

3. In a wear resisting and anti-slipping device for cushion heels, a device formed of a strip of sheet metal having substantially parallel edges and being formed with a 100 longitudinal aperture, one end of the strip being formed with a notch and turned at

right angles to the middle portion so as to form relatively sharp calks, the other end portion of the strip being formed with a bend at right angles to the middle portion, 5 said bend being at a line intersecting the said aperture, the strip being further provided with a bend between the first men-

tioned bend and the adjacent end of the strip to form a wear plate which lies substantially in a plane parallel with that of 10 said middle portion.

In testimony whereof I have hereunto set my hand.

BLAIR HARDESTY.
